UNITED STATES PATENT OFFICE.

ALBERT CHAMPION, OF FLINT, MICHIGAN, ASSIGNOR TO A C SPARK PLUG COMPANY, OF FLINT, MICHIGAN, A COMPANY OF MICHIGAN.

INSTRUMENT PANEL.

Application filed October 7, 1925. Serial No. 61,037.

This invention relates to means for supplementing the instrument carrying capacity of an instrument board. Its field of usefulness is obviously not limited to the specific application herein shown and described, but its immediate object is to serve to add a speedometer to the well known Ford automobile. In some of these vehicles a tank is placed so closely adjacent the instrument board that there is insufficient space for the location of a speedometer between the board and the tank. It is proposed to locate the speedometer wholly or partly below the board where more space is available. The means for so locating the speedometer consists of a plate serving to supplement the instrument carrying panel on the car whereby in a most convenient way a double panel may be used to accommodate the several instruments with substantially no change in the board.

For a full understanding of the invention reference is made to the following description and the accompanying drawing in which Figure 1 is a front elevation of the instrument board with the panel and instrument shown therein. Figure 2 represents in a similar view a modified form. Figure 3 is a vertical section on line 3-3 of Figure 1. Figure 4 is a vertical section on line 4-4 of Figure 2. Figure 5 is a plan view of the supplemental panel detached.

Referring to the drawing, and particularly to Figures 1 and 3, the numeral 1 represents the instrument board of the Ford automobile. In the car as equipped there are on this instrument board two instruments, a switch 3 and an ammeter 4. These instruments project forwardly through openings in the board and are mounted in a panel or plate 5 secured to the board. It is very desirable to add to the board a speedometer and it is in connection with such an addition that this invention is more particularly directed.

The instrument board has a raised portion 2 of general oval shape. From this raised portion is removed the panel found on the car which carries the two instru-

ments mentioned, and in the position occupied by this Ford panel is placed a supplemental panel 9 corresponding in shape at its upper part to the Ford panel but being elongated and extending below the board.

This supplemental panel is apertured as 6 at 6 to receive the instruments 3 and 4. The instrument panel 5 with its two instruments 3 and 4 is then placed over the supplemental panel in its former position and secured to the instrument board by fastening means 7, with the supplemental panel between it and the instrument board. The lower end of the supplemental panel carries through an opening 8 therein a speedometer 10 of well known type. The instrument board is shown as cut away at its lower edge to receive the speedometer (see Figure 1 and Figure 3). By a modified form (Figure 2 and Figure 4), if it be desired to bring the speedometer lower down or to avoid cutting or mutilating the instrument board the supplemental panel is made longer so that the speedometer lies wholly below the board. By the provision of this supplemental panel a symmetrical assembly of the several instruments is obtained. The speedometer is located in a position where it occupies ample space, and the change is accomplished with little or no change in the instrument board.

I claim:

The combination with an instrument board having therein normally a plurality of apertures adapted to receive instruments, of an adapter plate having apertures intended to register with the apertures normally existing in the instrument board and having also an aperture intended to receive an additional instrument, said adapter plate being placed adjacent to the instrument board and a closing plate normally carrying a plurality of instruments adapted to be placed in the apertures of the instrument board, said closing plate being placed over the adapter plate with the instruments in the registering apertures and securing means for the closing plate.

In testimony whereof I affix my signature.

ALBERT CHAMPION.
